BY *Chas. E. Townsend*.

ATTORNEY.

UNITED STATES PATENT OFFICE.

JOHN M. SCHAEDEL, OF SACRAMENTO, CALIFORNIA.

BEATING DEVICE.

1,402,380.

Specification of Letters Patent.

Patented Jan. 3, 1922.

Application filed July 27, 1921. Serial No. 487,926.

To all whom it may concern:

Be it known that I, JOHN M. SCHAEDEL, a citizen of the United States, residing at Sacramento, in the county of Sacramento 5 and State of California, have invented new and useful Improvements in Beating Devices, of which the following is a specification.

This invention relates to a stirring device, 10 and particularly pertains to a beater for use in connection with soda fountain mixers.

It is a principal object of the present invention to provide a simple attachment which may be instantly applied to the beater of a 15 soda fountain mixer and by which malted milk, milk shakes and other drinks may be rapidly beaten and caused to have a frothy appearance.

The present invention contemplates the 20 use of a metal member having a body portion adapted to encompass the beater of the usual motor-driven soda fountain mixer, and which member is formed with outwardly extending tangs adapted to thoroughly agitate the liquid within which it is 25 submerged.

The invention is illustrated by way of example in the accompanying drawings in which—

30 Fig. 1 is a view in side elevation showing the application of the present invention and indicating the invention in section;

Fig. 2 is an enlarged view in perspective showing the device with which the present 35 invention is concerned;

Fig. 3 is a view in plan showing the formation of the blank from which the present invention is made.

Referring more particularly to the drawings, 40 indicates a motor adapted to drive a vertical shaft 11. Mounted at the lower end of this shaft is a stirring device 12. This member may be circular or polygonal, and in either event it is intended that a 45 beater 13 shall be detachably secured thereto. At the present time the members 12 bring about their action due to their high speed of rotation and the centrifugal motion set up in the liquid. The present invention 50 contemplates the provision of agitating members which will tend to stir and beat the liquid in a more thorough manner than is now accomplished.

This beater is formed with a substantially circular central plate 14 which, in the present instance, is shown as hexagonal.

This plate is concaved to correspond with the usual convexed bottom of the stirring member 12. Formed as continuations of the facets of the body plate are upwardly extending portions 15 which are provided to embrace the sides of the stirrer 12, and which members are bent outwardly to lie in a plane substantially parallel to the central plate 14 where they form fingers 16. 60 The formation of this blank whereby the fingers are produced is more clearly shown in Fig. 3, where it will be seen that the side portions 15 and the fingers 16 gradually taper from the central plate 14, thus in a 65 simple manner forming a cup into which the stirrer 12 may be positioned and around the edges of which cup outwardly extending fingers occur. Protrusions 17 are formed in the side portions 15 and tend to slip around 70 and over the edges of the stirrer 12 to frictionally hold the beater in position, as shown in Fig. 1.

In the operation of the present invention the blank is formed, as indicated in Fig. 3, 80 and is thereafter bent along the score marks A and B to form the side portions 15 and the outwardly extending fingers 16. The member thus shaped may be fitted over a stirrer 12 of conventional design, and when 85 thus applied may be used to stir any liquid desired. It will be evident that the protruding fingers will produce a more satisfactory mixture of liquid, and at the same time will beat air into it to cause it to have 90 a frothy appearance.

When the device is to be washed it may be readily removed from the stirrer and instantly replaced.

While I have shown the preferred form 95 of my invention, it is to be understood that various changes may be made by those skilled in the art without departing from the spirit of my invention.

Having thus described my invention, what 100 I claim and desire to secure by Letters Patent is:

1. A device of the character described comprising a motor, a rotatable stirring rod, having a plunger at the end thereof, 105 an agitator having a central cup shaped portion adapted to clasp the plunger and radial fingers extending from the cup shaped portion.

2. An attachment for a beverage agitating device, comprising a cup shaped central base having upwardly extending elastic

- surrounding members to removably clasp the lower end of a rotatable stirring rod, said members being bent at the top to form horizontal outwardly extending radial fingers, convergent toward the ends.
3. A device of the character described adapted to be applied to the stirring element of a liquid mixer, comprising a central cup having a body portion conforming to 10 the bottom of the stirring element, and having yieldable side portions to clasp the stirring element and radial fingers extending from said side portions.
4. A device of the character described in combination with a motor and a stirring rod having a stirring element secured to the end thereof, of a member having a central cup shaped portion having yieldable side por-
- tions extending up and around the circumferential edge of the stirring element; the 20 said side portions terminating in fingers bent so as to extend radially.
5. A device of the character described in combination with a motor and a stirring rod having a stirring element secured at the 25 end thereof, of a member comprising a central cup having a body portion conforming to the bottom of the stirring element and having side portions adapted to extend up and around the circumferential edge of the 30 stirring element and clasp the same, the said side portions terminating in tapering fingers bent laterally so as to extend radially to provide agitating members.

JOHN M. SCHAEDLER.
